UNITED STATES PATENT OFFICE.

ERNEST E. HODSHON, OF NUTLEY, NEW JERSEY.

APPARATUS FOR BANDING HATS.

Original application filed July 5, 1923, Serial No. 649,621. Divided and this application filed May 21, 1924. Serial No. 714,856.

To all whom it may concern:

Be it known that I, ERNEST E. HODSHON, a citizen of the United States, and resident of Nutley, in the county of Essex and State 5 of New Jersey, have invented certain new and useful Improvements in Apparatus for Banding Hats, of which the following is a specification.

This invention relates to improvements 10 in apparatus for banding hats. The invention has for its objects to provide an efficient apparatus for applying and securing ornamental bands to hats in such manner that perspiration from the head of a wearer 15 cannot penetrate to the ornamental band; to provide an apparatus for applying bands to hats and simultaneously moisture-proofing the band; to provide an apparatus for attaching bands to hat crowns by means of 20 moisture-proof adhesive material; and to provide an efficient and economical apparatus for winding a strip of adhesive material and a length of ribbon in superposed relation around a hat crown and cementing the 25 ribbon to the crown by said strip of adhesive material.

The improvements are especially useful 30 for applying ornamental bands of ribbon to the crowns of soft or flexible felt or fabric hats, but may be employed for banding other types of hats.

In the drawings:

Figure 1 is a plan view of the apparatus;

Fig. 2 a side view, partly in vertical section;

Fig. 3 a vertical sectional view on the line 3—3 of Fig. 1;

Fig. 4 a vertical sectional view on the line 4—4 of Fig. 3;

Fig. 5 a vertical sectional view on the line 5—5 of Fig. 6, showing the electrically heated steaming nozzle;

Fig. 6 a horizontal sectional view on the line 6—6 of Fig. 5;

Fig. 7 a horizontal sectional view on the line 7—7 of Fig. 5;

Fig. 8 a vertical sectional view on the line 8—8 of Fig. 1 showing the means for supporting the roll of ribbon and the roll of adhesive material and exerting a drag on the ribbon and adhesive strip as they are wound around the hat crown;

Fig. 9 a horizontal sectional view on the line 9—9 of Fig. 8;

Fig. 10 a vertical section on the line 10—10 of Fig. 8 showing the feed-rolls which exert a drag on the ribbon and adhesive tape, the parts being in normal position;

Fig. 11 a detail sectional view on the same line as Fig. 8 showing the feed-rolls relieved 60 of pressure to facilitate passing the ends of a ribbon and an adhesive tape between the rolls;

Fig. 12 a plan view of the feed-rolls and the pressure device therefor;

Fig. 13 a detail view showing the construction of the hand-operated roller for pressing and smoothing or ironing the band after the band and adhesive tape have been wound about the hat and steamed; and 70

Figs. 14 to 19 are views graphically illustrating the manner of applying the bands to the hat with the apparatus shown in detail in the preceding views.

In the drawings the banding of a soft felt 75 hat has been illustrated. The general construction and arrangement of the apparatus and the manner of using the same in banding hats will first be described. The crown A of the soft felt hat is forced or pulled over 80 a suitable wooden hat block C until the under side of the brim B abuts against a rigid backing member such as a metal plate D. Block C and plate D are of elliptical form in end view and plate D projects a short distance 85 beyond the sides of block C entirely around the block so as to rigidly support the brim B adjacent its junction with the crown A.

The block and plate with the hat thereon are supported edgewise and driven in any 90 suitable manner to revolve about a horizontal axis extending centrally through the block and plate and centrally through the crown A of the hat from the top to the base 95 of the crown, and also to make two complete circuits around an orbital path during each single revolution about said axis. One means for so supporting and moving the hat, block and plate consists in holding the plate and block to a tubular shaft or sleeve 1 loosely mounted on a wrist pin 2 held to a crank arm 3 on a horizontal drive shaft 4, said sleeve 1 having a pinion 5 fixed thereon which is carried around inside a station-

ary ring gear or fixed annular rack 6 by the wrist pin, the pinion having twelve teeth and the ring gear or fixed rack having eighteen teeth.

- 5 The ornamental fabric hat bands are formed from successive lengths of ribbon severed from a roll of ribbon F and the hat bands are secured to the hat by gluing or cementing the same to the hat crowns by 70
10 successive lengths cut from a roll of material E in strip form adapted to become adhesive when heated. The adhesive material preferably consists of rubber cement in strip form, non-adhesive and moisture 75
15 proof at normal temperature but adapted to be rendered soft and "tacky" or adhesive by heating the same. This cement or adhesive is commercially known as tailor's mending tape.
- 20 The rolls E and F are wound on spools H and I, respectively, journaled on horizontal spindles J and K rigidly held at one end to one face of a metal plate G supported edgewise in a vertical plane extending transversely of wrist pin 2. One end of the plate G extends close to the edge of plate D and is adapted to deflect the outer part of hat brim B away from the crown A around the edge of plate D as the block C is rotated 80
25 so that strips F and E of ribbon and adhesive may be drawn from the spools to the crown of the hat with one edge of each strip abutting the brim at the junction of the brim with the crown. Plate G thus 85
30 prevents the soft flexible brim B of the hat from interfering with the winding of strips E and F about the crown A, and plate D braces the inner edge of the brim and holds it true and flat in a plane at a right angle 90
35 to the axis of rotation of the crown A so that the strips E and F may be wound accurately and smoothly around the base 95
40 of the crown with one edge of each strip in contact with the brim.
- 45 To wind the strips E and F about the crown the block is rotated by turning shaft 4 by means of a hand wheel 7 until one longer side of the elliptical crown A is uppermost. The free ends of strips E and F are then 100
50 temporarily fastened to the crown and block with strip E next to the crown by means of a fastening device O¹ preferably consisting of a metal bar having spurs or sharp prongs 105
55 adapted to be forced through the strips and crown and into the wooden block C. Shaft 4 is then rotated through two complete revolutions by wheel 7, or by a crank handle 8 fixed on the outer end of the shaft, in a 110
60 direction to wind the strips once around the crown with adhesive strip E under ribbon strip F. The parts of the strips encircling the crown are then severed from the 115
65 rolls at a point adjacent fastening device O¹ by scissors and the free ends of the strips are 120
70 then temporarily fastened to the crown and

block C by a fastening device O² adjacent device O¹. The lengths of strips E and F severed from the rolls are preferably slightly less in length than the circumference of the crown so that a slight gap will be left 70
75 between the ends of the strips fastened to the crown and block by devices O¹, O². Suitable means are provided for holding the strips E and F taut or under tension during the winding operation so that the strips 80
85 will be wound tightly and smoothly around the crown A. The tension means preferably consists of a pair of feed rolls L and M urged firmly toward each other by a bowed spring N the ends of which press on roll L. 85
90 The bite of the rolls on the strips and the drag exerted on roll L by the ends of spring N both contribute to maintain the strips taut during winding thereof about the hat crown.

A protecting cover P of canvas or other fabric, having a sheet of asbestos Q stitched on its upper face, is then laid over the portion of crown A not covered by the hat band E—F. Cover P—Q is secured at one end 95
100 to a standard S which supports plate G and has a combined weight and hand-grip R at its other end.

The cover is picked up by part R and passed over the crown and released, part R 95
105 serving to hold the cover firmly down upon the crown.

A steam nozzle and superheater T is then drawn to a position over the hat band E—F and rigidly supported by a slide bar 9 with 100
105 its discharge end spaced slightly above the hat band. The lower end of nozzle T is covered by a woven fabric cap U which causes the steam to issue in an evenly distributed cloud at low velocity over the entire area of the lower end of the nozzle which is preferably rectangular or square and of sufficient width to overlie the hat band at least from edge to edge of the band. The 110
115 nozzle is highly heated by an electric heating coil V wound spirally around the nozzle within the walls of the nozzle, electric current being supplied to the ends of the coil V by wires W¹ and W² of an electric cable W connected with a suitable source of electricity. Steam from a suitable generator is supplied to the nozzle T through a supply pipe Y having a pressure regulator or reducing valve X of ordinary construction 120
125 interposed therein. Regulator X is set to reduce the pressure of steam supplied to the nozzle to a low degree, preferably not more than three or four pounds, and the electrically heated nozzle is adapted to superheat this steam, so that dry steam at low pressure will issue from the nozzle. Injury to the finish of the ribbon F and damage to the hat crown under the hat by swelling or loosening the felt which would result from 130
135 subjecting the ribbon to a strong jet of wet

steam is thus avoided, and excessive moisture which would injuriously affect the action of the cement or unduly delay setting of the cement is avoided.

5 After the nozzle is brought over the band and the steam supply turned on by a suitable valve 10, the shaft 4 is rotated two revolutions at moderate and constant speed by means of crank handle 8. The band is 10 thus uniformly heated from end to end and from edge to edge by the steam issuing from the rectangular outlet of nozzle T, thus softening adhesive strip E and cementing the ribbon F to the hat crown. It will, of course, be understood that the hat may be 15 revolved several times if desired. The nozzle T is next moved away from the hat and fastening devices O¹ and O² are removed.

20 The hat may now be removed from block C and the cement allowed to dry or set, as the foregoing steps will firmly cement the band on the crown. Preferably, however, the band will be subjected to pressure to 25 insure it being tightly cemented to the crown without wrinkles or buckled portions. For this purpose, after the nozzle is withdrawn and devices O¹ and O² removed, and before removing the hat from block C, the block 30 is rotated until the adjacent ends of the band are at the under side of the block. A hand roller Z is then pressed down on the band at the upper said of the block which is then rotated approximately one-half a 35 revolution in the direction indicated by the arrow in Fig. 18 until the gap between the ends of band F reaches the roller. Roller Z is lifted and block C rotated until the 40 gap between the ends of the band is again at the under side of the block. Roller Z is then again pressed down on the band at the upper side of the block, which is then rotated in the direction indicated by the arrow in Fig. 19 until the gap between 45 the ends of the band reaches the roller. Any wrinkles or looseness in the band is thus rolled or pressed out, the spaced ends of the band moving nearer each other, and the band is pressed tightly against the crown 50 so that the adhesive will hold it firmly and smoothly in place when the adhesive cools and hardens. After the cement sets, the usual ornamental bow of ribbon may be secured to the band at one side of the crown 55 over the meeting ends of the band either by gluing or stitching the bow to the ribbon F.

60 The specific construction of the apparatus shown in the drawing will now be more fully described. The shaft 4 is journalled in bearings in the side members of an up-standing bracket 12 of inverted U-shape fixed to the top of a table 11. Handle 8 and hand wheel 7 are fixed on shaft 4 at opposite 65 sides of bracket 12, and crank arm 3 is fixed

on shaft 4 at one end of the shaft between hand wheel 7 and the annular, internally toothed gear 6. Gear 6 is clamped in the split head of a standard 13 and also is preferably keyed in said head as shown in 70 Figs. 3 and 4 to hold the gear stationary. Shaft 4 is in line with the axial line of gear 6. Wrist pin 2 is rigidly held at one end to the crank arm 3 and extends through gear 6. Pinion 5 is fixed on a sleeve or 75 tubular shaft 1 loose on wrist pin 2 so that said sleeve will be rotated about the wrist pin as the pinion is carried around in an orbital path inside gear 6 by movement of the wrist pin around the axis of 80 shaft 4.

The sleeve 1 projects through the center of elliptical metal plate D which is rigidly held to a radially slotted block or spider 85 14 keyed on the sleeve a short distance from the outer end of the sleeve. Block C is of elliptical form in end elevation to conform with the usual elliptical form of the hat crown A which, as usual, is elongated fore and aft of the hat (see Fig. 2 90 and Figs. 14 to 19). Block C is provided with a central recess 15 in its inner end in which the outer end of sleeve 1 is adapted to fit when the block is slipped on the sleeve, and is also provided with a circular groove 95 16 in its inner end surrounding the recess thus forming a central hub adapted to be firmly gripped by the jaws on the outer ends of a series of levers 17. Levers 17 are pivoted on block or spider 14 midway 100 their ends and extend through radial slots in the spider and radial slots in plate D. Links 18 connect the inner ends of levers 17 with a collar 19 loosely held in a circumferential groove in the hub of an adjusting hand wheel 20. The hub of wheel 20 is provided with internal screw threads and sleeve 1 is provided with external screw threads, so that by turning wheel 20 to cause 105 it to travel toward and from the outer end of sleeve 1 the jaws on levers 17 may be caused to grip the hub of block C to either hold the block to sleeve 1 to rotate about wrist pin 2 and simultaneously move in an orbit about the axis of shaft 4, or to release the block C to permit it to be removed from the sleeve for substitution of a smaller or larger block for holding a hat of a different size.

110 The metal plate G is provided with two circular flanges 21 and 22 surrounding the stub shafts J and K and enclosing the rolls of adhesive material E and band ribbon F on the spools H and I. The flanges are 115 preferably made deeper than the length of the stub shafts so that spools of material E and F of different widths may be slipped on the shafts and housed within the flanges, the spools being removably held in place 120 on the shafts by spring-pressed follower 125 130

disks 23 and 24 having stems 26 and 27 respectively, with squared portions slidable in square passages in bearing sleeves 28 and 29 formed integrally with a bar 30. Disks 23 and 24 are urged toward plate G by coiled tension springs 31 and 32, respectively, connecting sleeves 28 and 29 with stems 26 and 27. Flanges 21 and 22 are formed with slots 33 and 34, respectively, 10 at the upper side thereof through which strips E and F pass to the feed rolls L and M. Bar 30 is detachably clamped by thumb nuts 35 on the reduced threaded outer ends of posts 25 rigidly held at their 15 inner ends to plate G.

The trunnions of roller M extend through registering bearing apertures in plate G and the vertical arm of an angular bracket 36 rigidly held to the same face of the plate 20 as flanges 21 and 22, and the depending arms of an inverted U-shaped yoke 37 are pivotally held to the trunnions of said roller. The trunnions of roller L are journalled in vertical slots 38 in plate G and 25 the vertical arm of bracket 36, and said roller is pressed firmly toward roller M by a bowed spring N connected midway its ends to an adjusting screw 39 threaded in the cross-bar of yoke 37. The arms of 30 spring N pass through openings in the cross-bar of yoke 37 and frictionally engage and press down on roller L. The upper edges of 35 plate G and the vertical arm of bracket 36 are cut away slightly above roller L to provide stop shoulders 40 which engage in notches in the cross bar of the yoke 37 when the yoke is in normal position. The pressure on roller L may be relieved by 40 swinging the yoke rearwardly, as shown in Fig. 11, to facilitate the initial threading of the strips E and F between the rollers.

The plate G projects forwardly beyond the end of the table at which the operative stands and is connected near its rear end 45 by a hinge 41 with the upper end of standard S to permit the plate G together with the parts and devices thereon to be swung downward, as shown in dotted lines in Fig. 2, during the steaming and pressing operations, if desired, to permit the operative to 50 approach more closely this end of the table. This permits more convenient operation of the nozzle T and the treadle which operates steam control valve 10, and more convenient access to the hat for holding the 55 pressing roller Z. The plate G is supported in normal position by hinge 41, standard S, and a hinged prop or leg 42 the lower end of which is adapted to engage standard S 60 at the table top and the upper end of which is connected by a hinge 43 with plate G. Plate G lies in the same, or substantially the same, plane as plate D, and extends close to the outer edge of plate D, so that the 65 brim B of a hat on block C will be de-

flected slightly laterally around the edge of the plate D and held away from the path of the strips E and F during the strip winding operation. This is particularly useful in banding unblocked soft hats to 70 prevent the outer edges of the brims from interfering with the feed of the strips or deflecting the strips.

A drain cup or water collector 44 of ordinary construction is interposed in pipe Y 75 to reduce the amount of moisture passing to the nozzle T. A cut-off valve 45 is also interposed in pipe Y to shut off the steam when the apparatus is not in use, this valve being opened and remaining open during the 80 entire period of use of the apparatus. Pipe Y consists of a rigid metal pipe except for a flexible section Y¹ between the pressure-reducing valve and the steam-control valve 10, the section Y¹ being of sufficient length 85 to permit nozzle T to be slid back and forth to and from a position over block C, as indicated in Fig. 2. Pipe Y is connected to a steam generator, and pressure regulator valve X (which is of ordinary construction) 90 is adjusted to reduce the pressure of the steam delivered to nozzle T to a uniform low pressure, preferably about three or four pounds. The valve 10 is of ordinary construction and is normally held closed by 95 the steam pressure. The stem 46 of valve 10 is adapted to be pushed inwardly by a bell-crank lever 47 pivoted in a bracket 48 held to the valve casing upon depression of a treadle 49. Treadle 49 is pivoted at 100 100 on a support held to the legs of table 11 and extends to a point near the forward end of the table at which standard S is located so as to be in convenient reach of the foot of the operative who stands at that end of 105 the table. The treadle is normally held up by a spring 51 and is connected by a cord 52 with one arm of lever 47, said cord passing through a slot 53 in the top of table 11.

The end section of pipe Y in which valve 10 is interposed is bent upwardly and then downwardly upon itself below the valve to form a coil Y² consisting of three vertical lengths of pipe arranged side by side and enclosed within the reduced upper end of 110 the nozzle T, and the lower end portion Y³ of this pipe section is bent laterally under coil Y². The end of the lateral portion Y³ of the pipe is preferably closed by plugging or by pinching the end of the pipe flat, and said lateral portion is provided along its under side with a plurality of steam outlet holes 54.

The nozzle T comprises a tapered metal tube T¹ of rectangular or square cross-section across the smaller upper end of which the lateral outlet portion Y³ of pipe Y extends. A sheath T² of non-inflammable material which is a conductor of heat but a non-conductor of electricity extends 125 130

around tube T^1 and pipe coil Y^2 . The electric heating coil V of suitable resistance wire passes spirally around the outer side of the sheath T^2 and is connected at its upper end 5 to a binding post 55 and at its lower end to a binding post 56. The conductor wires W^1 and W^2 of an electric cable W leading to a suitable source of current (such as a lamp socket in an electric light fixture over 10 table 11) are connected to binding posts 55 and 56, respectively. The heating coil V and electric insulation T^2 are enclosed in an outer casing T^3 of non-inflammable, 15 heat-insulating material which is also a non-conductor of electricity. The tube T^1 is provided with a narrow steam deflecting tongue or baffle 57 extending under portion Y^3 of pipe Y and serving to prevent the steam from passing directly downward through 20 the nozzle in strong jets. This baffle deflects the steam toward the heated walls of tube T^1 so that steam, which has a temperature raised in passing through coil Y^2 , is still further heated as it passes through tube 25 T^1 . This superheating of the steam insures the delivery of very hot and dry steam from the nozzle. The lower end of the nozzle is covered by a cap U of woven fabric held to the nozzle by a cord or ring 58, said cap 30 acting as a steam diffusing means and also to still further retard the velocity of the steam and cause it to issue upon the hat band in a diffused evenly distributed cloud at low velocity.

35 The nozzle T is clamped on pipe coil Y^2 by a pair of clamps 59 having loops at their rear ends adapted to slip over the vertical arms of T-shaped screws 60. The shanks of screws 60 are adapted to be screwed into 40 different vertically spaced threaded sockets 61 in a bracket 62 to support nozzle T in proper relation with hat blocks C of different sizes. Bracket 62 is adjustably held to the forward end of a horizontally slid- 45 able bar 9 guided in a slideway in a block 63 screwed to a bracket 64 held to the top of table 11 near the rear end of the table. An adjusting screw 65 extends loosely through apertures 66 in bracket 62 and is 50 threaded through bar 9. As bracket 62 slidably engages the forward end of bar 9 and is seated on a pin 67 passing through the lower end of screw 65, it will be obvious that the bracket may be adjusted vertically 55 up or down by turning the screw. Screw 65 is used for slight adjustments of the nozzle which may be necessary in order to get the best results in steaming bands made of ribbon F of different weights and weave.

60 The canvas crown shield P is secured at its forward ends by screws or nails to standard S and has an upper layer or sheet of asbestos Q stitched thereto and a combined weight and hand-piece R at its free end.

65 The strip E of adhesive is preferably

more narrow than the ribbon F as shown, to avoid liability of the cement oozing out past the upper edge of the band during the steaming and rolling operations. The wooden pressing roller Z is journalled on a stub 70 shaft Z^1 fixed at one end to a suitable handle Z^2 , the stub shaft and handle being preferably arranged as shown in Fig. 13 so that one end of the roller Z may abut against the brim during pressing operations to permit 75 the roller to act on the ribbon throughout the width of the ribbon.

The mechanism for moving the hat block C through a circular orbit and simultaneously rotating the hat block about its axis is 80 so designed that the block is rotated about its axis one revolution during movement of the block through its orbital path two complete revolutions, that is pinion 5 rotates at one-half the speed of the shaft 4 and the 85 crank 2—3. To wind the band F and adhesive strip E entirely around the crown it is therefore necessary to turn crank handle 8 through two revolutions. It is also necessary to turn the crank handle two revolutions 90 to carry the band past the steaming nozzle from end to end. For each of the two smoothing operations by hand roller Z illustrated in Figs. 18 and 19 it is necessary to turn the handle through only one revolution. 95 The block operating mechanism maintains the highest point of the elliptical crown at approximately the same level throughout the winding, steaming, and rolling or pressing operations.

100 It will be noted that the band is maintained close to the discharge end of the steam nozzle during steaming of the band, that the steam discharging nozzle is so constructed that the steam is superheated at or 105 substantially at the point of discharge upon the band, and that owing to the construction of the electrically heated nozzle and the use of the low pressure reducing valve, coil Y^2 , and drip cup 44, the band and adhesive is 110 subjected to the action of a cloud of very hot and dry steam delivered upon the band at low velocity and uniformly distributed over the band from edge to edge.

115 This application is a division of my application, Serial No. 649,621, filed July 5, 1923.

What I claim is:

1. An apparatus of the class set forth comprising a hat block, means for rotating the 120 block about a horizontal axis, a vertically disposed steam discharge nozzle, means slidably supporting the nozzle to move laterally to and from a position overlying the block, and means adjacent the block for supporting 125 rolled strips of band ribbon and rubber cement.

2. An apparatus of the class set forth comprising a hat block, means for rotating the block about a horizontal axis, a verti- 130

- cally disposed steam discharge nozzle, means slidably supporting the nozzle to move laterally to and from a position overlying the block, and means carried by the nozzle for superheating steam supplied to the nozzle.
3. An apparatus of the class set forth comprising a hat block, means for rotating the block about a horizontal axis, a vertically disposed steam discharge nozzle, means slidably supporting the nozzle to move laterally to and from a position overlying the block, means carried by the nozzle for superheating steam supplied to the nozzle, and a fabric cap extending over the outlet end of the nozzle.
4. An apparatus of the class set forth comprising a hat block, means for rotating the block about a horizontal axis, a vertically disposed steam discharge nozzle, means slidably supporting the nozzle to move laterally to and from a position overlying the block, means carried by the nozzle for superheating steam supplied to the nozzle, a fabric cap extending over the outlet end of the nozzle, and a baffle in the nozzle between the inlet and outlet of the nozzle for directing the steam entering the nozzle toward the inner surface of the nozzle.
5. An apparatus of the class set forth, comprising a hat support, means for discharging steam toward the sides of the crown of a hat on the support in close proximity to the support, and means for superheating steam substantially at the point of discharge of said steam discharge means.
6. An apparatus of the class set forth, comprising a hat support, a steam discharge nozzle having a wide outlet, means for heating the walls of the nozzle, and means for supplying steam at a uniform low pressure to the nozzle.
7. An apparatus of the class set forth, comprising a steam discharge nozzle, a hat block, means for supporting the block on edge opposite the discharge end of the nozzle and rotating the block about an axis extending transversely of the nozzle, means at one end of the block forming an abutment perpendicular to the axis of rotation of the block for the brim of a hat pulled on the block from the other end of the block, and means for delivering strips of ribbon and adhesive material to the block in a path extending transversely of the axis of the block.
8. An apparatus of the class set forth comprising a drive shaft, a crank arm held to said shaft, a wrist pin held to the crank arm, a sleeve mounted on the wrist pin to travel in a circular orbit with said pin and rotate about the pin, a pinion fixed on the sleeve, a stationary circular internal rack arranged in axial alignment with the drive shaft and encircling the pinion so that the teeth of the pinion mesh with the teeth of the rack as the pinion is carried around the rack by the wrist pin, the rack and pinion being so constructed that the pinion will be rotated once around its axis for each two revolutions of the drive shaft and crank arm, and an elliptical hat block held at one end centrally thereof to the sleeve to rotate therewith.
9. An apparatus of the class set forth comprising a drive shaft, a crank arm held to said shaft, a wrist pin held to the crank arm, a sleeve mounted on the wrist pin to travel in a circular orbit with said pin and rotate about the pin, a pinion fixed on the sleeve, a stationary circular internal rack arranged in axial alignment with the drive shaft and encircling the pinion so that the teeth of the pinion mesh with the teeth of the rack as the pinion is carried around the rack by the wrist pin, the rack and pinion being so constructed that the pinion will be rotated once around its axis for each two revolutions of the drive shaft and crank arm, an elliptical hat block held at one end centrally thereof to the sleeve to rotate therewith, a steam discharge nozzle adjacent one side of the block, means for supplying steam to the nozzle, and means for heating the walls of the nozzle.
10. An apparatus of the class set forth comprising a drive shaft, a crank arm held to said shaft, a wrist pin held to the crank arm, a sleeve mounted on the wrist pin to travel in a circular orbit with said pin and rotate about the pin, a pinion fixed on the sleeve, a stationary circular internal rack arranged in axial alignment with the drive shaft and encircling the pinion so that the teeth of the pinion mesh with the teeth of the rack as the pinion is carried around the rack by the wrist pin, the rack and pinion being so constructed that the pinion will be rotated once around its axis for each two revolutions of the drive shaft and crank arm, an elliptical hat block held at one end centrally thereof to the sleeve to rotate therewith, a steam discharge nozzle adjacent one side of the block, means for supplying steam to the nozzle, and means for heating the walls of the nozzle.
11. In an apparatus of the class set forth, the combination of a crank having a wrist pin, means for turning the crank, a sleeve loose on the wrist pin, a hat block elliptical in end view held at one end to the outer end of the sleeve, means for rotating the sleeve about the wrist pin upon rotation of the crank, and a flat plate fixed on the sleeve at the inner end of the block and having its outer edge projecting beyond the sides of the block to form an abutment for the brim of a hat on the block.
12. In an apparatus of the class set forth,

- the combination of a crank having a wrist pin, means for turning the crank, a sleeve loose on the wrist pin, a hat block elliptical in end view held at one end to the outer end 5 of the sleeve, means for rotating the sleeve about the wrist pin upon rotation of the crank, a flat plate fixed on the sleeve at the inner end of the block and having its outer edge projecting beyond the sides of 10 the block to form an abutment for the brim of a hat on the block, and a ribbon spool supported at one side of the block with one end thereof in substantially the same plane as said plate.
- 15 13. In an apparatus of the class set forth, the combination of a crank having a wrist pin, means for turning the crank, a sleeve loose on the wrist pin, a hat block elliptical in end view held at one end to the outer end 20 of the sleeve, means for rotating the sleeve about the wrist pin upon rotation of the crank, a flat plate fixed on the sleeve at the inner end of the block and having its outer edge projecting beyond the sides of the 25 block to form an abutment for the brim of a hat on the block, a ribbon spool supported at one side of the block with one end thereof in substantially the same plane as said plate, a pair of tension rollers between said 30 spool and block, and spring means urging said rollers toward each other to grip a ribbon therebetween.
14. An apparatus of the class set forth comprising means for supporting a roll of ribbon and a roll of adhesive material in strip form, a hat block, means for rotatably supporting the hat block, a pair of rollers, means rotatably supporting the rollers between the hat block and said ribbon and 35 adhesive roll supporting means, and means for urging the rollers toward each other to grip a ribbon and an adhesive strip therebetween.
15. An apparatus of the class set forth comprising a horizontally slidable support, a vertically disposed nozzle having an outlet at its lower end, means for supplying steam to said nozzle, means for connecting said nozzle for movement with said support 40 in various vertically adjusted positions relative to the support, and means below the path of horizontal movement of the nozzle for rotatably supporting hat blocks of different sizes for revolution about a horizontal 45 axis.
16. An apparatus of the class set forth comprising means for rotatively supporting a hat, a steam discharge nozzle, means supporting the nozzle to move to and from a 50 position to deliver steam against the crown of a hat supported by the said hat supporting means, and means adjacent the block for supporting rolled strips of band ribbon and rubber cement.
- 60 17. An apparatus of the class set forth comprising means for rotatably supporting a hat, a steam discharge nozzle, means supporting the nozzle to move to and from a position to deliver steam against the crown of a hat supported by the said hat supporting means, and means adjacent the block for supporting rolled strips of band ribbon and rubber cement.
- 65 18. An apparatus of the class set forth, comprising a hat support, means for discharging steam toward the sides of the crown of a hat on the support in close proximity to the support, and electrical means for superheating steam substantially at the point of discharge of said steam discharge means.
19. An apparatus of the class set forth comprising a hat support, means for discharging steam toward the sides of the crown of a hat on the support in close proximity to the support, means for delivering steam at a uniform pressure to said discharge means, and means for superheating said steam substantially at the point of discharge of said steam discharge means.
20. An apparatus of the class set forth comprising a rotatable hat block, means for discharging steam toward the sides of the crown of a hat on the block in close proximity to the block, means adjacent the block for supporting rolled strips of band ribbon and rubber cement to be wound about the base of the hat crown by attaching their outer ends to the hat and rotating the block, and means to yieldingly resist the feed of 100 said strips to the hat crown and thereby tension the strips as they are wound upon the crown.
21. An apparatus of the class set forth comprising a hat support, a nozzle for discharging steam toward the sides of the crown of a hat on the support, a steam-pressure reducing valve, means for delivering steam to said valve, means for delivering steam at reduced pressure from said valve to the discharge nozzle, and means for superheating the low pressure steam substantially at its point of discharge from the nozzle.
22. An apparatus of the class set forth comprising a rotatable hat block, means for discharging steam toward the sides of the crown of a hat on the block, and a flexible shield adapted to cover and rest upon the outer portion of the hat crown and to permit the block and hat to rotate relatively thereto.
23. An apparatus of the class set forth comprising a rotatable hat block, means for discharging steam toward the sides of the crown of a hat on the block, and a removable shield adapted to cover the outer portion of the hat crown.
24. An apparatus of the class set forth comprising a rotatable hat block, means for 130

discharging steam toward the sides of the crown of a hat on the block, and a movable flexible shield hingedly supported at one end adjacent the block and adapted to cover 5 and rest upon the outer portion of the hat crown and to permit the block and hat to rotate relatively thereto.

25. An apparatus of the class set forth comprising a rotatable elliptical hat block, 10 a steam discharge nozzle, means supporting the nozzle with its discharge end directed toward the periphery of the block, and means to maintain a fixed spaced relation between the block and the nozzle as 15 the block is rotated.

26. An apparatus of the class set forth comprising an elliptical hat block, means to rotate the block, a steam discharge nozzle, means supporting the nozzle with its dis-

charge end directed toward the periphery 20 of the block, and means operable by the said block-rotating means to maintain a fixed spaced relation between the block and the nozzle as the block is rotated.

27. An apparatus of the class set forth 25 comprising a rotatable hat block, a steam discharge nozzle, means supporting the nozzle to move to and from a position to deliver steam against the crown of a hat supported by the block, a foot-operated valve 30 to control the discharge of steam from said nozzle, and means adjacent the block for supporting rolled strips of band ribbon and adhesive material.

In testimony whereof I hereunto affix my 35 signature.

ERNEST E. HODSHON.
